DRYING RACK

Shirley Zeper, 8448 Forrest Ave., Philadelphia, Pa.
Filed May 11, 1962, Ser. No. 193,981
2 Claims. (Cl. 211—105.1)

This invention relates to a drying rack and in particular to an improved rack for drying wet garments such as bathing suits, etc.

Traveling conditions for car travelers in the United States have improved rapidly within recent years. Many motels boast, in addition to the usual television sets, swimming pools both indoor and outdoor. These pools are finding great favor with travelers, especially in southern climates all year round and in northern zones during the summer months. Despite all of these improvements, however, most motel operators have not yet provided any special and effective apparatus which would enable the traveler to have his wet bathing suit dry out quickly enough to enable it to dry by the next day for use again or to be packed for the next day's travel. Consequently, the traveler must resort to whatever equipment is at hand in order to attempt to dry out his suit.

Very often the guest will place the bathing suit over a radiator which may or may not be heated. If it is, when the guest wishes to pack the suit the next day, he will find that it has dried into a corrugated mass whose contours follow the contours of the radiator. Besides, the water from the suit drips onto the floor causing a messy and dangerous pool. The radiators are often rusty and leave spots on the garments. Sometimes the guests will drape the wet suit over the shower curtain rod and the water in the suit will drip onto the bathroom floor. Also, in these makeshift arrangements, since the front and rear parts of the bathing suit are very close to one another, not much air can circulate in-between and the drying process is considerably retarded. Still other guests hang their bathing suits on a wire or wooden hanger and somehow suspend the top part of the hanger from an appropriate point. The expedient often has the disadvantage that the bathing suit is so heavy that it will deform the wire hanger and possibly slip to the floor or, if it does not fall, does not permit much air to circulate between the front and rear portions of the suit and hence drying is a very slow process. Wooden hangers, though stronger and more rigid, easily become ruined by water, which may cause warping and discoloration. Even these hangers do not spread the front and rear portions sufficiently far apart to permit drying, and it is difficult to hang more than one suit on each hanger. As is the case with wire hangers, wooden hangers do not separate the front and back portions of the suits sufficiently to enable good circulation of air through them.

From the standpoint of the motel owner, this lack of convenient and adequate inside hanging equipment often induces the guests to hang their suits outside on a railing which may be located near the pool. Here, again, the front and rear parts of the suit are pressed against one another. Besides, this presents a very unesthetic appearance to the other guests and also to prospective guests.

While it would be very advantageous for the motel owner and his guests to provide equipment for use inside for drying bathing suits and other wet garments, this equipment should preferably be capable of being installed permanently into the motel premises to avoid loss of it through theft.

2

It is, therefore, an object of the present invention to provide a novel rack for drying wet cloth objects.

Another object of the invention is to provide a simple drying rack for wet garments, which is constructed to accelerate the drying process.

Another object of the present invention is to provide a drying rack for wet garments that may be installed so as to avoid dripping of water from the garments onto floors.

Another object of the invention is to provide a drying rack for wet garments, which promotes more rapid drying of the garments by enabling better circulation of air through them.

Still another object of the invention is to provide a novel drying rack for wet garments, which does not discolor or distort the shape of the garments.

Another object of the invention is to provide a drying rack onto which the wet garments may be easily placed and withdrawn and is constructed to prevent said garments from sliding off.

Yet another object of the invention is to provide a novel drying rack for wet garments, which may be permanently installed in motels and the like, without taking up any substantial amount of useful space.

Other objects of the invention may be appreciated from a reading of a specification and claims herein taken in conjunction with the drawings in which:

FIGURE 1 is a perspective view of one form of my invention;

FIGURE 2 is a front elevation view of another form of my invention;

FIGURE 3 is an enlarged and partly sectional detail of a corner of the apparatus shown in FIG. 2 taken along the section lines 3—3 in the direction indicated;

FIGURE 4 is a side elevation view of my invention in another of its forms; and

FIGURE 5 is a perspective view of the apparatus shown in FIG. 4.

FIGURE 6 is a plan view, partly in phantom, of still another embodiment of my invention.

In accordance with my invention, I have devised an inexpensive and practical drying rack, which is characterized by having dimensions such that when the wet garment is placed, by means of an appropriate opening in the garment, over the rack, the opposite parts of the garment will be spaced from one another sufficiently for air to circulate freely therein, so as to speed up the drying process. In one form of the invention, an elongated, transversely corrugated horizontal member, having turned-up ends, is employed. The corrugations abet the circulation of air under the part of the garment which is suspended on the rack, and the turned-up ends prevent the wet garments from slipping off, should the rack flex somewhat under the weight of it. In another form of the invention, the rack may be made from a single piece of plastic, which is folded back on itself at each end and then folded inwardly and twisted to form two horizontal projections, whose free ends are spaced from one another to permit insertion and withdrawal of wet garments upon the horizontal portions. The vertical part of this rack may then be affixed to an appropriate wall.

In still another form of the invention, the rack may be made from a single piece of elongated plastic material, which is folded, so that it will have a section generally resembling an elongated C. The rack is disposed with the bottom of the C member screwed or otherwise affixed to the wall of a bathtub-shower combination, for ex-

ample, while the top of the C-member is disposed around the shower curtain rod. Since the rack is suspended between the shower wall and the shower curtain, the dripping clothes will drip only on the inside of the bathtub and hence will not produce troublesome puddles of water on the floor.

Referring to FIGURE 1, one form of my invention is shown, which comprises a flat vertical section 10, which is affixed by screws 11 or other appropriate fasteners to a vertical wall or other member. A horizontal elongated portion 12 has a number of transverse corrugations 13 formed therein and is connected to the vertical section 10, or is formed integral therewith. When wet garments 14 are placed with their shoulder straps 14a over the section 12, the corrugations 13 tend to keep the shoulder straps 14a spaced from one another, even if the left part of the elongated member 12 should bend down somewhat under the weight of the garments. The corrugations also promote air circulation, if the wet suit is put on the rack by passing the horizontal portion 12 through the trunk opening of a pair of bathing shorts, for example, and out one of the leg openings. Also, since the portion 12 has a substantial front-to-back depth, the front and back sides of the garments are spaced well away from one another, so that air can circulate through the suit thereby speeding up the drying process. The material, of which the parts 10 and 12 are made, should not be corrodible, lest the corrosion stain the garments. For this reason, a rigid plastic material is to be preferred.

Referring now to FIGURES 2 and 3, another form of my invention is shown, which may be easily formed out of a single elongated piece of plastic material, for example. It comprises a vertical wall-mounting section 16, which includes respective left and right folded-over portions or projecting sections 17 and 18, and flat, horizontally-disposed portions 19 and 20, extending toward one another and terminating in turned-up portions 21 and 22. As in the first embodiment of my invention, the portions 19 and 20 have a front-to-back depth, sufficient to separate the front and back portions of the wet garments, for instance, by at least several inches to permit the passage of air. The space between the turned-up portions 21 and 22 permits the shoulder strap or other opening in the wet garments to be passed over the portions 19 and 20. The turned-up ends 21 and 22 prevent the garments from slipping off, should the weight of the wet garments tend to pull down the horizontal portions 19 and 20. If desired, the portions 19 and 20 may be corrugated to help in circulating the air and in keeping the shoulder straps of the wet garments separate from one another. As in the first embodiment, the entire rack should be made of a non-corrosive material to prevent staining of the garments.

FIGURE 4 shows still another embodiment of my invention and includes a horizontal flat portion 26, an end portion 27, which is substantially perpendicular to the top 26, an opposite end portion 28, which is curved somewhat to fit around a shower curtain rod 29, and two horizontal flat portions 30 and 31 extending inward toward one another. The portions 30 and 31 have respective turned-up ends 32 and 33 spaced from one another to permit the wet garments 14 to be inserted onto the portions 30 and 31. One or more holes (not shown) are bored in the end portion 27 to permit one or more screws 36 to pass through it and to be screwed into a wall or other supporting member 37. These screws 36 will make the installation permanent and discourage attempts to remove it from public places like hotels and motels, for example. One or more bolts 38 (see also FIG. 5) are passed through apertures (not shown) in the portions 26 and 31 and fastened by nuts 39 to assist in preventing removal of the rack and also to prevent movement of the end portion 28 away from the rod 29 when the heavy wet garments are placed on the portion 31. The same effect can be achieved by forming in either or both of the portions 26 and 31 an upwardly or downwardly-extending

ridge or boss not shown) right next to the rod 29. These ridges exert a compressive force on the rod 29.

It should be appreciated that the portion 26 can be made in two sections (not shown), which partially overlap and have a number of holes therein. By aligning the holes with one another and passing bolts through them, the two sections may be connected for any desired length. If the length is longer than the span from the bathtub wall to the rod, no permanent fastening devices like screws 36 are necessary to hold the left portion 27 up. Of course, left portion 27 will be somewhat longer to compensate for the fact that the section 26 is tilted up at the wall end, so that the portion 30 can be substantially co-planar with portion 31. With this arrangement the traveler can carry his own rack from motel to motel.

FIGURE 6 shows still another form of my invention which includes a wall-mounting portion 40 having two upper flanged portions 40a and 40b. The left flange 40a has formed therein a curved slot 44 and an aperture (not shown) in which downwardly depending pegs or pins 43 and 42 are respectively disposed. These pins are connected at the left end of clothes supporting member 41. Member 41 ordinarily is supported by the flanges 40a and 40b when supporting clothes to be dried or when not in such use. When clothes are to be hung the member 41 is pivoted toward the user (clockwise as seen in FIG. 6) and the shoulder strap or crotch portions are slipped over it whereupon it is then pivoted away from the user (counter-clockwise FIG. 6) and its right end is brought to rest upon flange 40b. The reverse procedure is employed in taking the dry clothes off.

If desired, the pins 42 and 43 may be provided with transverse holes near the lower ends to enable clothes pins or similar devices to be inserted after the pins are placed in their respective hole and slot in flange 40a. This prevents member 41 from being dislodged from flange 40a during the loading and unloading operation.

Still other variations which do not depart from the essence of my invention will occur to those skilled in the art. Consequently, I desire my invention to be limited only by the following claims.

I claim:

1. A unitary rack for drying apertured wet garments comprising: a substantially flat elongated section of sheet material for connection to a supporting surface, first and second projecting sections of sheet material respectively connected to said elongated section at each end thereof and extending generally transverse thereto, and two garment-engaging sections of sheet material connected respectively to said first and second sections and extending inwardly therefrom toward one another with their respective free ends spaced from each other, said garment-engaging sections being substantially flat and relatively wide for preventing substantially all of the opposing inner surfaces of garments slipped thereover from touching one another, and said garment-engaging sections being disposed substantially perpendicular to said elongated section and to said first and second projecting sections.

2. The unitary rack according to claim 1 wherein said elongated section, said projecting portions and said two garment-engaging sections are all formed out a single piece of plastic material, wherein said projecting portions are bent outwardly from said single piece at two points substantially equidistant from the ends thereof, and wherein in said garment-engaging sections are co-planar and have corresponding inner edges substantially close to said elongated section.
